VEGETABLE PEELER

Myrtise M. Murphree, Hapeville, Ga.

Application November 26, 1956, Serial No. 43,931

Term of patent 14 years

(Cl. D22—3)

Fig. 1

Fig. 2

Fig. 3

Fig. 4

Fig. 5

Fig. 1 is a top plan view of a vegetable peeler showing my design.

Fig. 2 is an end elevational view thereof as seen from the right of Fig. 1.

Fig. 3 is a side elevational view.

Fig. 4 is another end elevational view as seen from the left of Fig. 1.

Fig. 5 is a bottom plan view thereof.

I claim:

The ornamental design for a vegetable peeler, substantially as shown.
